UNITED STATES PATENT OFFICE.

SVEN SWANSON AND OSCAR SWANSON, OF CHICAGO, ILLINOIS.

COMBINED RAIL JOINT AND CHAIR.

1,157,452.

Specification of Letters Patent. Patented Oct. 19, 1915.

Application filed July 24, 1915. Serial No. 41,744.

To all whom it may concern:

Be it known that we, SVEN SWANSON and OSCAR SWANSON, subjects of the King of Sweden, residing at Chicago, in the county of Cook and State of Illinois, have invented 5 certain new and useful Improvements in Combined Rail Joints and Chairs, of which the following is a specification.

The present invention relates to improvements in fastening means for joining railway 10 rails, the object in view being to provide a device accomplishing this function without utilizing bolts, thereby eliminating the use of parts subject to loosening and displacement, and at the same time, one which 15 greatly facilitates the operation of connecting the rail ends.

Our invention consists of a rail chair, 20 clamping means having interlocking connection therewith and adapted to coöperate with the fishplates, and means for actuating said clamping means to cause clamping action; it is further contemplated to employ a locking element coacting with the fishplates and 25 the rails and with which the clamping means also coöperates to prevent displacement.

With the above and other objects in view, 30 this invention consists in the construction, combination and arrangement of parts all as hereinafter more fully described, claimed and illustrated in the accompanying drawings, wherein:

Figure 1 is a vertical sectional view 35 through a device constructed in accordance with our invention, and showing its application to the rail joint. Fig. 2 is an end elevation thereof. Fig. 3 is a top plan view. Fig. 4 is a horizontal sectional view taken on the plane indicated by the line 4—4 of 40 Fig. 2. Fig. 5 is a perspective view of a clamping member of this device.

Throughout the following detail description, and on the several figures of the drawings, similar parts are referred to by like 45 reference characters.

Referring to the drawings, the numerals 1, 1, designate the rail extremities which are to be joined and 2, 2 the fishplates therefor. These fishplates are located as usual at the 50 side of the rails engaging the webs thereof and the said parts are provided with suitable apertures to receive a transverse locking pin 3 passing through the fishplates and the rails. The rails seat upon a chair 4 which 55 projects laterally from the rails at each side and is formed at its end portions with trans-

verse recesses 5 therebeneath. The chair 4, as will be particularly noted by reference to Fig. 4, is formed at each side with longitudinally extending slots 6 each leading to a recess 5 at the respective side.

In Fig. 5 of the drawings is illustrated a clamping member which is used in conjunction with this device, said clamping member being designated 7 and having formed at one end thereof a transverse head 8 making the clamping member somewhat T-shaped in formation. Adjacent to the other end of the clamping member is an upstanding arm 9 having one side thereof formed with a groove 10 and just beneath this groove is located an opening 11 extending through the clamping member. At the opposite side or in the face of the arm extremity is formed a recess 12 which is adapted to receive an end 75 of the locking pin 3 hereinbefore mentioned. It will be understood that a clamping member 7 is provided at each side of the rails and said clamping members are first interlocked with the chair by inserting the upstanding arms 9 through the slots 6 and positioning the heads 8 in the transverse recesses 5. When in this position, the chair is disposed beneath the rail extremities and spikes 13 are driven into the tie 14 on which 80 the chair is located, said chair being provided with openings to receive these spikes which when driven home engage the base flanges of the rail, as shown in Fig. 3.

In order to obtain a proper clamping action 90 of the fishplates against the rail webs, spike-like wedge members 15 are introduced into the grooves 10 of the upstanding arms 9 of the clamping members, through the openings 11 therebeneath and into the tie. 95 Owing to the wedge-shape of these members, as they are driven downwardly into place, the clamping members 7 are actuated and caused to clamp against the fishplates at opposite sides of the rail. In order to obtain 100 a positive action of the wedge members 15, the chair is preferably formed adjacent to each end thereof with an upstanding projection 16, the inner face of which is formed with serrations 17 with which the serrated faces 18 of the wedge members 15 engage when they are driven into position. This construction prevents the displacement of the wedge members and also enables the adjustment thereof when necessary from wear 105 tending to loosen the parts of the device.

It will be observed in Fig. 1, that the rail

chair 4 is formed with a shoulder 19 at the end of each of its longitudinal recesses 6, said shoulder being adapted to receive a projection 20 on the inner end of its adjacent 5 clamping member 7. This acts to guide the movement of the clamping member and prevents binding of the same when the wedge member 15, coacting therewith, is driven into position.

10 It will be obvious from the foregoing description, that the device enables the joining together of rail extremities without the necessity of employing the bolts customarily utilized for attaching fishplates and which 15 bolts very often become loose, resulting in a separation or spreading of the rails and accidents necessarily following such separation. The dispensing with bolts of this character enables the device to be quickly 20 positioned, thereby saving considerable time in the process of connecting rails.

Having thus described the invention, what we claim as new is:

1. In combination, rails, fishplates there- 25 for, a rail chair, a clamping member having an upstanding arm adapted for engagement with a fishplate, means interlocking said clamping member with the chair, and means interposed between the arm of said clamp- 30 ing member and the chair for causing clamping action of a fishplate.

2. In combination, rails, fishplates there- 35 for, means locking said plates to the rails, a chair, clamping means movably engaging the chair and coöperating with the locking members aforesaid for preventing displacement thereof, and means for holding said clamping means in coöperative relation with respect to the locking means.

40 3. In combination, rails, fishplates there- for, means locking said plates to the rails, a chair, clamping means movably engaging the chair and coöperating with the locking means aforesaid for preventing displacement thereof, and adjustable means adapt- 45 ed to be introduced intermediate the chair and the clamping member and having a positive engagement with the chair for holding the clamping member in clamping position.

Copies of this patent may be obtained for five cents each, by addressing the "Commissioner of Patents, Washington, D. C."

4. In combination, rails, fishplates there- 55 for, a rail chair, a T-shaped clamping mem- ber having interlocking connection with said chair, said clamping member being formed with an upstanding arm adjacent to one end for engaging a fishplate, and a wedge shaped actuating member adapted to be driven between the arm of the clamping member and the rail chair, said clamping member having a recess through which said 60 wedge shaped member passes whereby to cause clamping action of said clamping member with respect to a fishplate.

5. In combination, rails, fishplates there- 65 for, a locking pin passing through said fish- plates and the rails, a rail chair on which said rails are seated, a movable clamping member disposed at each side of the rails and adapted for engagement with the fish- 70 plates, each of said clamping members hav- ing a head for interlocking with the rail chair, said clamping members having re- cesses to receive the locking pin for pre- 75 venting displacement of the latter, and means interposed between the clamping mem- bers and the chair for actuating the former to cause clamping action.

6. In combination, rails, fishplates there- 80 for, locking means for said fishplates and rails, a rail chair on which said rails are seated, said chair being formed with trans- 85 verse recesses adjacent to its extremities, and longitudinal slots formed therein at each side of the rails, clamping members, each of said clamping members being of T- shaped formation for seating in the recesses of said chair above mentioned, arms formed on said clamping members projecting through the slots for engagement with the fishplates, wedge members interposed be- 90 tween the arms of the clamping members and the chair, and means on said chair co- 95 acting with the wedge member for positively holding the latter in adjusted positions.

In testimony whereof we affix our signatures.

SVEN SWANSON.
OSCAR SWANSON.
